UNITED STATES PATENT OFFICE.

PUZANT R. YUZUK, OF NEW YORK, N. Y., ASSIGNOR TO GENERAL ELECTRIC COMPANY, A. CORPORATION OF NEW YORK.

DETACHABLE PLUG.

No. 921,196.

Specification of Letters Patent.

Patented May 11, 1909.

Application filed August 17, 1907. Serial No. 368,948.

To all whom it may concern:

Be it known that I, PUZANT R. YUZUK, residing at New York, county of New York, State of New York, have invented certain new and useful Improvements in Detachable Plugs, of which the following is a full, clear, and exact description.

My invention relates to detachable plugs for electric circuits, and has for its object to provide a two-part plug, one part of which may be left permanently in the socket of a fixture connected to the circuit, and the other part of which can be readily connected to and disconnected from the first part, said plug being provided with fuse links which will melt and break the circuit in case of an over-load or short circuit. Heretofore two-part detachable plugs by which I mean plugs whose base and terminal bearing parts can be separated and connected without the aid of any tool or instrument, have not been provided with fuse links and the result has been that where such plugs have been used in connection with wall fixtures or chandeliers, the only point in which protection against over-load or short circuit could be provided for was within the fixture or chandelier, usually at its base. In such instances, when an overload or short circuit occurred, the fixture or chandelier fuse would be blown and the fixture or chandelier as a whole put out of commission, and various other dangers and troubles would occur. In order to avoid this difficulty, I have provided a safety fuse within the plug itself, this fuse being so proportioned as to blow out at the proper time, and protect the chandelier fuse, thus removing all the difficulties above referred to.

The following is a description of a plug embodying my invention, reference being had to the accompanying drawings, in which—

Figure 1 shows a side elevation of said plug; Fig. 2 shows an upward projection of the base member of the same; Fig. 3 shows a section on line $x-x$ of Fig. 2; Fig. 4 shows a section of the device of Fig. 1 on line $y-y$ (Fig. 3); Fig. 5 shows the terminal-bearing member withdrawn from its position; Fig. 6 is a downward plan view of the cap or cover, which fits on the device shown in Figs. 2 and 3; Fig. 7 is a downward plan view of the terminal-bearing member shown in Fig. 5; Fig. 8 is a side elevation of a modification; Fig. 9 is a section of the same on line $x-x$ of Fig. 11; Fig. 10 is a partial section on line $y-y$ of

Fig. 11; Fig. 11 is an upward projection of Figs. 9 and 10; Fig. 12 is a perspective view of the cover or cap of Fig. 8; Fig. 13 is a side elevation of the terminal-bearing member; and Fig. 14 is a plan view of the same. 60

Referring more particularly to the drawings, A represents the base portion of the plug, B represents the cover portion, and C represents the detachable bearing portion. Within the recess in the base portion A are 65 terminals D—D, one of which is secured to an external screw-threaded terminal E by screw e, while the other is secured to a plate F by screw f. Within the screw-threaded portion E is a porcelain plug G, on the bottom of which is a contact-plate H. A screw I passes through this contact-plate and the plug G into the plate F, securing these parts and the base A together. Within the recess of the base A are secured terminal plates 75 J—J, carrying spring-clips K—K. The plates J—J are secured within the recess by screws j, j. The two terminals D are connected to their neighboring terminal plates J by fuse wires L—L, by means of ordinary 80 binding screws, as shown. Upon the base A is secured the cap or cover B by means of screws b, passing through the wall of the base and into reinforcing plates b², secured to the cap or cover by screws or rivets. The 85 cap or cover is provided with openings B', which, when the cover is in place, lie directly over the spring-clips K—K. Between these openings and on each side of the plates J—J are depending walls B², which surround the 90 spring terminals K—K and approach very closely to the bottom of the base A, particularly between the terminals K—K and also between the terminals D and K, which are connected to opposite poles of the circuit, 95 thereby introducing an insulating wall between the parts connected to the opposite poles and preventing the formation of any arc between them.

The terminal member C is provided with 100 two flat terminals C'—C' for engagement with the clips K—K. The terminals C'—C' are connected to the flexible conductors C² (as shown in Fig. 7), the portions C'—C' being provided with suitable binding screws 105 and being themselves secured to the terminal bearing portion C, by screws or rivets in any suitable manner.

In operation, the screw-threaded portion E is placed in the lamp socket in the ordinary 110

manner and the terminals C'—C' are readily forced into or moved from the clips K—K by a direct movement, thus obviating all twisting of the conductors C'. When the device 5 is in use, as, for instance, on a motor or other apparatus which has a varying load and the circuit becomes over-loaded, the fuse wires L—L blow when the over-load point is reached, and before the fuse in the chandelier 10 blows, thereby preventing trouble and injury which would otherwise occur when the chandelier fuse is alone relied on.

In the modification shown in Figs. 8 to 14, the same result is accomplished. In this 15 case, 1 is the base portion, 2 is the cover portion, and 3 is the terminal-bearing portion. To the base portion terminal members 4—4 are secured by screws passing through the bottom of the base portion. One of these 20 terminal portions is connected by its securing screw to a lug 5, which is soldered to a metallic screw-threaded terminal 6, in the upper end of which is secured a piece of porcelain or non-conducting material 7, on the 25 bottom of which a terminal-plate 8 is secured by a screw 9 passing through the same, and into a plate 10, which is electrically connected to the other terminal-plate 4 by its securing screw. Within the base portion are also 30 terminal-plates 11, which are secured thereto by screws passing through the bottom of the base. These plates 11 are provided with spring-clips 12, which are adapted to engage terminals upon the terminal-bearing portion 35 3. The plates 4 and 11 are all provided with ordinary binding screws, and each plate 4 is connected to its neighboring plate 11 by a fuse wire 13. The cover 2 is provided with lugs 14, into which pass screws 15 through 40 holes 16, securing the parts together. The cover is provided with a depending projection 17, which fits into grooves 18 and, therefore, determines the proper position of the cover. The inner portion 19 of this projection 45 extends downward into the base until it approaches the bottom of the base, when the cap or cover 1 is in position, thus forming a partition separating the two poles of the circuit, and preventing any arcing directly 50 between the two poles when the fuse blows. The cap or cover 1 is provided with two openings 21, which, when the cover is in place, lie directly over the spring contacts 12, and through which the terminals 22, secured 55 to the contact-carrying member 3, may be readily inserted and withdrawn. These terminals 22 are secured to the contact-bearing member 3 by screws or rivets in any ordinary manner, and are provided with binding 60 screws 23 to which the ends of the flexible conductors 24 are connected in the ordinary manner, as shown in Fig. 14.

My invention permits of being embodied in various other forms and can be modified in various ways, without departing from the 65 broad principles employed therein.

What I claim is—

1. In a detachable plug, the combination of a base portion adapted to be inserted in a socket, a terminal-bearing portion readily 70 detachable therefrom, links of fusible metal interposed in the circuit and adapted to be carried by said base portion, and a cover secured to said base portion so as to be between said base portion and said terminal-carrying portion, said cover having openings 75 for the terminals carried by said terminal-bearing portion.

2. In a detachable plug, the combination of an insulating base portion, contacts mounted on the front side thereof, means located on the back side of said base portion for securing it to a socket and electrically connecting said contacts to the circuit, a terminal bearing portion readily detachable from 80 said base portion, and said contacts, a fuse link interposed in the circuit and carried by said base portion on its front side, and a cover secured to said base portion and situated between the front side of said base portion and said terminal bearing portion, said cover having openings 85 for the terminals of said terminal bearing portion.

3. In a detachable plug, the combination of a base portion having terminals and adapted to be secured to a lamp socket, a terminal-bearing portion readily detachable therefrom, links of fusible metal interposed in the circuit and carried by said base portion, a cover secured to said base portion so as to be between 90 said base portion and said terminal-carrying portion, said cover having openings 95 for the terminals carried by said terminal-bearing portion, and an insulating partition separating the poles of the circuit within the 100 base portion adjacent to said links.

4. In a detachable plug, the combination of a base portion adapted to be secured to a lamp socket, a terminal-bearing portion readily detachable therefrom, links of fusible 110 metal interposed in the circuit and carried by said base portion, a cover secured to said base portion so as to be between said base portion and said terminal-carrying portion, said cover having openings for the terminals 115 carried by said terminal-bearing portion, and said cover having a depending wall lying between the two poles of the circuit within said base, adjacent to said links.

PUZANT R. YUZUK.
